UNITED STATES PATENT OFFICE.

GEORGE L. CARRUTHERS AND JAMES S. HOLDERNESS, OF PINE BLUFF, ARKANSAS.

CIRCUIT-CLOSING APPARATUS.

1,193,510.

Specification of Letters Patent.

Patented Aug. 8, 1916.

Application filed March 2, 1916. Serial No. 81,716.

To all whom it may concern:

Be it known that we, GEORGE L. CARRUTHERS and JAMES S. HOLDERNESS, citizens of the United States, residing at Pine Bluff, 5 in the county of Jefferson and State of Arkansas, have invented certain new and useful Improvements in Circuit-Closing Apparatus, of which the following is a specification.

Our invention relates to coin actuated means for closing a circuit, and to automatically open the circuit, after it has been closed for a predetermined length of time.

An important object of the invention is to 15 provide means of the above mentioned character, which is simple in construction, inexpensive to manufacture, and reliable in operation.

Other objects and advantages of the invention will be apparent during the course 20 of the following description.

In the accompanying drawings forming a part of this specification and in which like numerals are employed to designate 25 like parts throughout the same, Figure 1 is a side elevation, partly diagrammatic, of apparatus embodying the invention. Fig. 2 is a side elevation, parts broken away, of an endless belt and associated elements, 30 and, Fig. 3 is a horizontal sectional view taken on line 3—3 of Fig. 1.

In the drawings, wherein for the purpose of illustration is shown a preferred embodiment of our invention, the numeral 5 designates an electric motor of any well known or preferred construction, having an armature shaft 6. The numeral 7 designates a fly-wheel, carried by the armature shaft 6, and represents the load. This fly-wheel, due 40 to inertia, in the operation of the motor, will prevent the sudden stopping of the motor, whereby the motor will operate for a short time after its circuit is broken.

The motor is connected in a circuit including wires 8 and 9, as shown. Connected in the wire 9 is a source of current 10.

The coin controlled mechanism comprises a base 11, upon which are rigidly mounted upstanding posts 12. The upper ends of the 50 posts 12 are connected by horizontal strips 13 and these posts are connected by lower strips 14, as shown. Connected with one post 12 and insulated therefrom is a stationary contact 15, having connection with the wire 8. This contact 15 is rigidly secured upon a bracket 16. This post 12 is

provided with a horizontal pin or pivot element 17, upon which is mounted to swing in a vertical plane a movable contact 18, to engage and disengage the stationary contact 15. This movable contact is insulated from the pivot element 17. The upper end of this pivoted contact carries a depending weight-arm 19, adapted to engage with a transverse stop member 20, when the contact 18 is in the lowered or opened position. The pivoted contact 18 has connection with the wire 9, as shown. The arm 19 is heavier than the contact 18 and automatically swings the same to the open position.

The numeral 21 designates a preferably vertically arranged stationary coin chute, suitably connected with the upper horizontal strips 13, and having its lower end arranged between pivoted coin chute sections 22 and 23. The coin chute section 23 is rigidly attached to the pivoted contact 18 but is thoroughly insulated therefrom. The co-acting coin chute section 22, is pivoted to the strips 13 at its upper ends, as shown at 24.

The coin chute section 22 is moved inwardly or to the active position by means of a spring 25, attached to one post 12, as shown. Connected with the lower end of the coin chute section 22 is a depending arm 26, arranged upon the outer side of a stationary stop 27, adapted to limit its inward movement. Pivotally connected with the lower end of the arm 26 is a pitman 28, having pivotal connection with the lower end of a bell crank lever 29, pivoted at 30. As more clearly shown in Fig. 2, the outer end of the bell crank lever 29 is preferably beveled or inclined, as shown at 31, and is adapted to engage with a trip wedge or member 32, secured upon an endless belt 33. This endless belt is driven by a roll 34, secured to the armature shaft 6.

In operation, the coin is deposited in the upper end of the coin chute 21 and moves 100 downwardly by gravity and enters the coin chute sections 22 and 23. The spring 25 is sufficiently stiff to normally hold the coin chute section 22 against movement by the action of the coin, while the coin swings the 105 coin chute section 23 outwardly, causing the pivoted contact 18 to engage the stationary contact 15. This closes a circuit to drive the motor 5, current flowing in this closed circuit from one side of the source of current 110 10, a portion of the wire 9, through the motor 5, wire 8, stationary contact 15, pivoted

contact 18, and through the other portion of the wire 9 back to the opposite pole of the source of current. The apparatus is arranged to allow the motor to operate for a predetermined period for driving any suitable mechanism, such as mechanical dolls arranged in a vending machine or the like, while the invention is in no sense restricted to such use. The rotation of the armature shaft 6 of the motor drives the endless belt 33, causing the wedge 32 to be advanced toward the bell crank lever 29. When the wedge 32 engages the bell crank lever 29, it swings the same upon its pivot, causing the pitman 28 to move to the right and swing the coin chute section 22 to the right. This movement of the coin chute section 22 releases the coin, allowing it to drop from within the coin chute sections 22 and 23. When this takes place the coin chute section 23 is then free to return to its inner position, the same being swung thereto by the weight of the arm 19, which moves downwardly to contact with the stop 20. The coin chute 22 is moved sufficiently to release the coin chute when the wedge 32 is about to trip the lever 29, but the inertia of the flywheel 7 after the circuit is opened, will cause the motor to continue its operation for a sufficient length of time, whereby the wedge 32 will trip the lever 29 and pass therebeyond. When this occurs, the spring 25 automatically returns the coin chute section 22 to its inner active position.

It is to be understood that the form of our

invention herewith shown and described is to be taken as a preferred example of the same, and that various changes in the shape, size, and arrangement of parts may be resorted to without departing from the spirit of the invention or the scope of the subjoined claim.

Having thus described the invention, we claim:

In apparatus of the character described, a circuit, a motor connected in the circuit, a frame, a contact device for opening and closing the circuit supported by said frame and comprising a stationary contact member supported by the frame, a pivoted contact member having adjacent its contact end a depending weighted portion whereby it is normally held out of contact and having at its opposite end a coin contacting member, a co-acting coin contacting member pivoted near the first named coin contacting member, a coin chute delivering between the said coin contact members, motor operated means to automatically move the second named coin contacting member to the outer position when the motor has operated for a predetermined time.

In testimony whereof we affix our signatures in presence of two witnesses.

GEORGE L. CARRUTHERS.
JAMES S. HOLDERNESS.
